FLASHLIGHT LAMP

Paul Schwarze, St. Gallen, Switzerland

Application September 14, 1937, Serial No. 163,828
In Germany September 21, 1936

6 Claims. (Cl. 67—31)

The known flashlight lamps of the type, in which light is produced by the reaction of suitable substances, enclosed in gas tight vessels, are complicated and expensive to manufacture. They generally comprise glass bulbs in the form of ordinary incandescent lamps and contain aluminum foils as light developing substance. As the oxygen required for the combustion can only have a very slight pressure, in order to avoid explosions, it is necessary to provide comparatively large glass bulbs for producing sufficient light. This renders the conveyance of large quantities, as is necessary for example in the case of photo-reporters, rather difficult. A further defect of the known lamps is that in spite of the slight oxygen pressure the lamps sometimes explode and it has happened that this has led to fires and injuries. Hitherto it has not been possible in practice to eliminate entirely this dangerous explosion of the flashlight lamps, although experiments have shown that when the lamp is ignited the pressure developing within the lamp is generally not greater than atmospheric. The reason is to be sought in the inaccuracy of manufacture, because otherwise the costs of production of an article which can only be used once would be rendered prohibitive in practice, and further in the fact that the glass bulbs often have inner stresses as they come from the glass works, further stresses being developed when the base is fused into the lamp. Owing to these stresses, the bulbs are sometimes caused to explode by minute incandescent metal parts hurled against the glass walls when the flashlight charge is ignited. It has also been tried to produce flashlight lamps with openings, covered by easily destructible foils, in order to compensate for the increase of pressure, but they necessitate additional devices to prevent the issuance of the flame and smoke.

According to the present invention these defects of the known flashlight lamps are eliminated by making the flashlight vessel of a gas tight, tough material, e. g. metal, preferably in the form of a flat box closed by a window for the passage of the light and consisting of a gas tight material offering sufficient resistance to the combustion pressure occurring, for example reinforced or non-splinterable glass or even common glass of sufficient strength. In this way the quantity of oxidizable material necessary for sufficient illumination may be housed in a considerably smaller vessel than hitherto and when necessary the oxygen may be maintained therein at a correspondingly higher pressure. Experi-

ments have proved that the gas charge can be increased to atmospheric or even higher pressure, if suitable material of sufficient strength is used. The sealing of the window is effected with the aid of vacuum cement, white sealing wax or the like but in order to prevent the intrusion of air reliably in all transport, storage or climatic conditions the parts to be sealed may be firmly pressed to one another by means of suitable devices or suitable shaping, preferably by screwing on, with the interposition of a packing of rubber or the like.

In the accompanying drawing embodiments of the invention are illustrated by way of example.

Figs. 1, 2 and 3 are sections through a flashlight lamp according to the invention.

In Fig. 1, the flashlight lamp consists of the box 1 of gas tight, tough material, e. g. metal. It is filled with a flashlight charge, adapted to emit light by reaction of its components, as for instance metal in the form of foil or powder and oxygen. 2 is a disc of special or ordinary glass of sufficient strength, which closes the box in an air tight manner with the aid of the vacuum cement 3. 4 is a primer with the aid of which the flashlight substance is ignited, in the embodiment shown in Fig. 1 mechanically, for example through a firing pin.

A further useful arrangement of the flashlight lamp is illustrated in Fig. 2. The lower part of the box 1 is the combustion chamber, which is closed by the transparent skin or pane 5 and which contains the flashlight charge. Above this there is a space 8, which is sealed in a gas tight manner by the window 2. The space 8 acts as a buffer chamber or receiving space for the combustion pressure. The pressure in same is conveniently of the same value as in the combustion space. In this figure 9 indicates openings for the evacuation of the air and for charging the oxygen. These openings may be closed by pinching or with vacuum cement or the like. In this embodiment the ignition is provided in the well known electrical form. 4 is the igniting filament, one end of which may be directly attached to the box if this is made of conductive material.

Fig. 3 shows an embodiment in which for better sealing the window is pressed to the box by screwing it on. In this figure 3 is a packing ring of rubber, leather or the like. 5 is a Cellophane skin which may at one point be provided with a fine hole. 7 is the lid, the side edges of which are formed with a thread corresponding to that of the box 1. The major part of the upper side of the lid is apertured for the window 2 and the

remaining ring presses the window against the packing 3 and the upper edge of the metal box 1 when the lid is screwed on. The Cellophane skin 5 resists the first gas pressure at the combustion and also serves to receive the precipitate of the residues of combustion, thereby keeping the window clean. This skin may however be omitted. The box and window may also be pressed together by other means, for example by 10 springy stirrups or by clamping suitable substances between the disc 2 and the ring 7 and so forth. The form shown in Fig. 3 may also be embodied by making the whole box 1 of glass and forming 2 as a closed metal lid without a disc. 15 This embodiment would in exterior appearance resemble the well known preserve jars.

The flashlight charge to be employed is not shown in the figures. It may consist of foils, metal powder or other oxidizable material together with oxygen gas or of any other solid or gaseous substances which on reacting produce light. If flashlight mixtures are utilized consisting of metal powder with oxygen yielding substances the combustion space can be wholly or 25 partly evacuated. If two reacting gases are employed, one gas may be introduced into each of the two spaces shown in the embodiment according to Fig. 2, since greater durability is ensured by the separation of the gases. In the latter 30 case the primer can be provided on the skin 5, so that this may be pierced upon ignition, thereby bringing about the reaction of the gases.

For evacuating the boxes and filling them with oxygen or other gases of atmospheric pressure they may have instead of the opening or openings 35 9 shown in Fig. 2, a plain hole of extremely small diameter. They can then be placed in considerable numbers in receptacles for evacuation and refilling and the small holes can subsequently be sealed in any convenient manner without any 40 considerable loss of gas.

The flashlight lamp according to the invention has the additional great advantage, especially in the embodiment shown in Fig. 3, that the main 45 parts may be used again by refilling them with a new flashlight charge, which is impossible in the known flashlight lamps consisting of glass bulbs.

What I claim as my invention and desire to secure by Letters Patent of the United States is:

50 1. A flashlight lamp particularly for photographic purposes, comprising a vessel of gas tight, tough material; a transparent window for the passage of the light, sealed to an opening of said vessel in a gas tight manner and adapted to resist the combustion pressure produced; a flashlight charge in said vessel adapted to emit light by reaction of its components; and means for igniting said charge within the said vessel.

sist the combustion pressure produced; a flashlight charge in said vessel adapted to emit light by reaction of its components and means for igniting said charge within said vessel.

2. A flashlight lamp particularly for photographic purposes, comprising a vessel of gas tight, tough material; a window of transparent material sealed to an opening of said vessel in a gas tight manner and adapted to resist the combustion pressure produced; a second window of 10 transparent material, separated from the first by an interspace; a flashlight charge in said vessel adapted to emit light by reaction of its components and means for igniting said charge within the said vessel.

3. A flashlight lamp particularly for photographic purposes, comprising a vessel of gas tight, tough material; a window of transparent material sealed to an opening of said vessel in a gas tight manner by being pressed on to it with the 20 interposition of a packing and adapted to resist the combustion pressure produced; and a flashlight charge in said vessel adapted to emit light by reaction of its components.

4. A flashlight lamp particularly for photographic purposes, comprising a vessel of gas tight, tough material, the side edges of which are formed as screw threads; a lid adapted to be screwed on to said vessel by means of corresponding screw threads in its side edges; a window of 30 transparent material in the lid; and a flashlight charge in said vessel adapted to emit light by reaction of its components.

5. A flashlight lamp particularly for photographic purposes, comprising a vessel of gas 35 tight, tough material; a transparent window for the passage of the light, sealed to an opening of said vessel in a gas tight manner and adapted to resist the combustion pressure produced; a flashlight charge in said vessel consisting of oxidizable metal and oxygen at substantially atmospheric pressure and means for igniting said charge within the said vessel.

6. A flashlight lamp particularly for photographic purposes, comprising a box-shaped vessel of gas-tight, tough material; a transparent window for the passage of the light, sealed to an opening of said vessel in a gas-tight manner and adapted to resist the combustion pressure produced; a flashlight charge in said vessel adapted 50 to emit light by reaction of its components; and means for igniting said charge within the said vessel.

P. SCHWARZE.
